UNITED STATES PATENT OFFICE.

JAMES J. NEWELL, OF ADRIAN, MICHIGAN.

APPARATUS FOR GENERATING HEATING AND ILLUMINATING GASES.

SPECIFICATION forming part of Letters Patent No. 314,871, dated March 31, 1885.

Application filed March 26, 1884. (No model.)

To all whom it may concern:

Be it known that I, JAMES J. NEWELL, a citizen of the United States, residing at Adrian, in the county of Lenawee and State 5 of Michigan, have invented certain new and useful Improvements in Apparatus for Generating Heating and Illuminating Gases, of which the following is a specification, reference being had therein to the accompanying 10 drawings.

My invention relates to the manufacture of heating and illuminating gases from petroleum or other liquid hydrocarbons, superheated steam, and air; and it consists of an 15 apparatus having a furnace, a series of retorts with suitable connections, means by which the steam is superheated, an atomizer in which the hydrocarbon is vaporized, and an injector in which the superheated steam 20 and air are blended and forced into the atomizer, all so arranged as to act automatically, whereby the vaporized hydrocarbon and gases evolved from the steam and air are decomposed and combined so as to form fixed gas.

25 The object of my invention is to produce heating and illuminating gases at a small percentage of the cost at which they are now produced by any known apparatus or process by an apparatus simple in construction, readily 30 understood, easy of adaptation to manufacturing or other establishments, practical and uniform in its operation, and certain in its results.

I am aware that heating and illuminating 35 gases have been manufactured from hydrocarbon oils, steam, and air by different apparatuses and processes; but so far as I have been able to learn such apparatuses and processes have not proven to be of great utility 40 or commercial value.

By my apparatus and process I overcome the difficulties heretofore experienced, and am able to manufacture and produce said gases of any desired heating capacity or illuminating-power of which fixed gases are capable. 45 I am also able by my apparatus to enrich or dilute natural gases flowing from fissures in the earth to any required standard.

In the drawings similar letters of reference 50 indicate like parts.

Figure 1 is a front view of my apparatus, showing the location of the furnace, the re-

torts, and the leading-in and connecting pipes. Fig. 2 is a plan view showing the atomizer, the leading-in, connecting, and distributing 55 pipes. Fig. 3 is a side elevation of my apparatus, partly broken away, showing a gang of pipes on the side of the furnace for superheating the steam in part, the atomizer, leading- 60 pipes, and drip-pipe attached to the atomizer, through which water and other deleterious substances may be eliminated. Fig. 4 is a rear end view of my apparatus, showing the retorts, connecting and distributing pipes, and test-jet. Fig. 5 is a vertical cross-section of 65 my apparatus. Fig. 6 is a longitudinal vertical section of my apparatus, showing the construction of the furnace, location of the gas-burner, flue, retorts, and pipes. Fig. 7 is a top view of the gas-burner. Fig. 8 is a section view of the injector.

A represents the brick structure containing my apparatus, constructed with two compartments—an upper and lower—the lower compartment for the furnace, and the upper to 75 contain the retorts and be used as a retort-heating chamber.

B represents the lower compartment, and B' the upper.

The lower compartment is constructed, preferably, of a rectangular oblong shape, as shown in Fig. 6, extending backward nearly the entire length of the brick structure, having a flue near the front end to convey the flame and heat to the upper chamber, and a grate 85 to support the fuel or gas-burner. The interior of this chamber is lined with fire-brick. On either side of this chamber, and outside of the course of fire-brick, are spaces, as shown in Figs. 3 and 5, extending the entire length 90 thereof, to receive gangs of pipes for superheating the steam.

The upper compartment is constructed, preferably, in a nearly semi-cylindrical shape, as shown in Fig. 5, extending nearly from one 95 end of the brick structure to the other, lined with fire-brick, and provided with suitable means for sustaining the retorts.

C, C², C³ and C⁴ are retorts, made of hollow iron cylinders or tubes, arranged and supported as shown in Fig. 5, and extending from end to end of the brick structure, as shown in Fig. 6. These retorts may be of any desired diameter, C⁴ being about twice the diameter 100

of C', C², and C³, and are preferably arranged as shown, but may be otherwise arranged, if desired.

5 D, the atomizer, is a hollow iron tube, of about one-half the diameter of the retorts C' C² C³, extending the entire length of the brick structure, but exterior thereto, and having suitable openings for the injector, the hydrocarbon-feed pipe, the drip-pipe, and connecting-pipe with retort C' on the rear end.

E is the injector, having entrance and exit openings a' a'', nozzle b, sleeve c, and chamber d. The opening a'' is into atomizer D, as shown in Fig. 8.

15 F F' are gangs of pipes for superheating the steam in part in the spaces on the sides of the fire-chamber.

F² is a similar gang of pipes in retort C⁴, connected to gang F' by pipe h, where the superheating of the steam is completed.

f is a pipe to convey the steam from any steam-chamber to gang F.

g is a pipe to convey the steam from gang F to gang F'.

25 h is a pipe to convey the steam from gang F' to gang F².

i is a pipe to convey the steam from gang F² to injector E.

j is a pipe with openings j' j'' for the admission of air or natural gas, and connected to injector E.

k is a pipe to convey hydrocarbon to atomizer D.

l is a drip-pipe, with a suitable stop-cock, 35 extending below injector E to carry off any water which may be condensed in retort C⁴ or pipe i.

m is a drip-pipe, with suitable stop-cock, 40 extending below atomizer D to carry off any water or deleterious substances which may be condensed in the atomizer.

n n are pipes connecting the retorts in front, and n' is a pipe connecting retorts C² and C³ at the back end.

45 o is a pipe connecting atomizer D with retort C'.

pp'p'' are pipes to convey the gas, when fixed, either to a furnace or to a gas-holder.

G is a gas-burner consisting of a hollow tube 50 constructed in three parts, as shown in Fig. 7, in the shape of a horseshoe, and perforated on the upper side to allow the gas to escape. This burner may be inserted in the fire-box, as shown in Fig. 6, being connected by pipe 55 to retort C⁴, or to the gas-holder after sufficient gas has been manufactured to heat the furnace instead of heating with coal or other fuel. It may also be used with proper connecting-pipe to generate steam in the furnace 60 under the steam-boilers.

r is a door opening into the fire chamber.

The operation of my invention is as follows: The steam generated in any boiler conveniently located is conveyed to the gang-pipes 65 F through pipe f, from thence through pipe g to gang F', from thence through pipe h to gang F². The steam passing through these

gangs, which are kept at a very high degree of heat, is superheated, and in this condition is conveyed from gang F² through pipe i to 70 injector E, passing in at opening a, and thence to atomizer D. As the steam passes opening a' in the injector a vacuum is formed in chamber d, which draws in the air, which, blending with the steam, these together take 75 up the hydrocarbon coming into atomizer D through pipe k and vaporize the same. The vapor thus formed passes through atomizer D into retort C' through pipe o, from thence by pipe n to retort C², from thence by pipe n' to 80 retort C³, and from thence by pipe n to retort C⁴, where it is converted into a fixed or cured gas. The gas is formed by passing the vapor issuing from atomizer D over the heated inner surfaces of the several retorts. When so 85 formed, it is carried by pipes p p' from the retort C⁴ to the furnace for use, or by pipe p'' to the gas-holder.

When the gas formed is to be used for heating purposes, it need not be subjected to any 90 further treatment. When it is to be used as an illuminating-gas, it should be cleansed by passing it through a "wisher" or "scrubber" of any well-known construction.

I am able by my apparatus herein described 95 to enrich or dilute natural gases flowing from fissures in the earth. When it is desired that such natural gases should be enriched, I pass the same into injector E in place of the air, and convey it into the atomizer D with the 100 steam, where it comes in contact with the hydrocarbon issuing from pipe k, vaporizing the hydrocarbon, and the vapor thus formed from steam, natural gas, and hydrocarbon is conveyed into the retorts, combined and fixed, 105 the same as vaporized hydrocarbon, as above described. When it is necessary to dilute the natural gases, the hydrocarbon is cut off and the air and natural gas and steam are 110 united and pass into the atomizer. By the union of the air and steam with the natural gas the same is diluted, and may be made of any degree of richness below its natural state required.

Having thus described my invention, what I 115 claim, and desire to secure by Letters Patent, is—

1. In an apparatus for generating heating and illuminating gases from atmospheric air, petroleum or other hydrocarbons, and superheated steam, the combination of a heating-chamber, one or more retorts for decomposing and fixing the gases, an injector, and a tubular atomizer of approximately the same length as the retorts exterior to said chamber 125 in which the petroleum or other hydrocarbons are vaporized and then blended with the steam and air, substantially as described.

2. In an apparatus for generating heating and illuminating gases from atmospheric air 130 and petroleum or other hydrocarbons and superheated steam, the combination of a fire-chamber with gang-pipes on either side thereof and adjacent thereto, a heating-chamber con-

taining a series of retorts to fix the gases, an atomizer of tubular form exterior to said chambers provided with a drip-pipe, and an injector so constructed as to blend the superheated steam and air before the same comes in contact with the hydrocarbon, substantially as described.

3. In an apparatus for generating heating and illuminating gases from atmospheric air and petroleum or other hydrocarbons and superheated steam, a fire-chamber with gang-pipes for superheating the steam adjacent

thereto, a heating-chamber containing a series of retorts one of which contains a gang of pipes for completing the superheating of the steam, an atomizer, an injector, and a test-jet to determine the quality of the gases produced, substantially as described.

In testimony whereof I have affixed my signature in presence of two witnesses.

JAMES J. NEWELL.
